UNITED STATES PATENT OFFICE

2,056,252

WRINGER

John B. Castino, River Forest, Ill.

Application March 1, 1934, Serial No. 713,486

12 Claims. (Cl. 68—32)

This invention relates to wringers and more particularly to a wringer of the type conventionally attached to a power-driven washing machine.

5 An object of the invention is to provide a wringer combining a maximum of safety and a quick means for reversing its rotation.

A further object of the invention is to provide a reversing mechanism which is operable by 10 manually tilting a wringer roll in either direction from the vertical center line.

Another object is to provide a simplified and 15 efficient reversing mechanism more economical of manufacture than are similar devices now in use.

In the drawings:—

Fig. 1 is a side elevational view of a wringer apparatus embodying my invention.

Fig. 2 is a view on line 2—2 of Fig. 1.

20 Fig. 3 is a view in vertical section of the reversing apparatus unmeshed.

Fig. 4 is a fragmentary view of Fig. 3 showing the device meshed to rotate the wringer rolls in one direction.

25 Referring more particularly to the drawings, the numeral 10 designates a vertical shaft which may be connected to any source of power. At the upper end of the shaft 10 is fixed a spiral gear 11, shown in dotted lines in Fig. 1. A pair 30 of spiral gears 12 and 13, are set at right angles to gear 11 and are in constant mesh therewith. The gears 12 and 13 are fixed on shafts 14 and 15, the latter being rotatively mounted in the wringer head 16.

35 The wringer proper is supported in a frame 17, having a base board 18. The lower wringer roll 19 has a shaft 20 fixed therein which is freely supported in the bearings 21 and 22 which, in turn, rest on the trapped coil expansion springs 23, 23', 24, (not shown) and 24'. The upper 40 wringer roll 25 has a shaft 25a which is journaled in the cams 26 and 27, which latter are integral with the handle member 28. In the position shown in Fig. 3 the upper roll 25 may be 45 freely lifted out of the assembly by means of the handle 28.

The frame 17 is provided with longitudinally extending inwardly disposed detent pins 29, 29', 30, (not shown) and 30'.

50 The shafts 14 and 15 carry a pair of spur gears 31 and 31', on the ends thereof adjacent the upper wringer roll 25. A spur gear, 32, is fixed on the end of shaft 25a, adjacent the gears 31 and 31'; the latter being so spaced as to separately mesh with gear 32, if and when the handle 28 and roll 25 are tilted in either direction from 55 vertical central alignment.

The cams 26 and 27 have detents as at 33 and 33' designed to impinge against the pins 29, 29', 60 30 and 30'.

In operation, the source of power will rotate the shaft 10 with the spiral gears 11, 12 and 13 and the spur gears 31 and 31'. Assuming that the handle 28 is in vertical position, the gears 31 and 31' will rotate free and clear of the spur 5 gear 32. To rotate the wringer rolls it is necessary to tilt the handle 28 transversely of the rolls, thus forcing the detents on one side of the handle under the adjacent detent pins. This action will securely engage the spur gear 32 with the 10 rotating spur gear 31 or 31'. The spur gear 32 will always engage the gear adjacent the upper side of cam 26. In the engaged position the mesh is securely held by the pinioning of the detents under the related pins, and the contact of the 15 upper sides of the cams 26 and 27 with the opposite pins together with the contact of the upper and lower rolls 25 and 19 as well as the contact of the meshed gears.

It is to be understood that other methods and 20 structures may be employed to maintain the gears in mesh.

Various modifications in structure and design 25 may be used in producing the device without departing from the spirit of the invention or the scope of the appended claims.

Having thus described my invention, what I claim and desire to secure by Letters Patent of the United States is:—

1. In a wringer of the class described, a source 30 of power, a vertical drive shaft associated therewith, a gear on the head of said shaft, a pair of horizontal shafts, a pair of gears on the latter in mesh with the vertical shaft gear, a wringer roll, a gear fixed on one end thereof, a pair of 35 gears on said horizontal shafts adjacent the roll gear, and means for shifting the wringer roll whereby the roll gear may be meshed with either of said shaft gears.

2. A reversible wringer comprising a frame, a 40 rotatable roll fixed therein, a rotatable roll movable laterally with reference to the frame, a gear fixed on said movable roll, a pair of spaced normally reversely rotating driving gears, and manual means for swinging the movable roll from a 45 perpendicular center line drawn midway between the centers of the driving gears in either direction to mesh its gear with either of said driving gears.

3. In a reversible wringer, a manually shiftable wringer roll, vertical driving means constantly in mesh with horizontal twin driving means and adapted for opposite rotation, a gear on said wringer roll, and gears on said horizontal driving means positioned to mesh with the gear 55 on said roll when the latter is shifted.

4. In a reversible wringer, a frame, a fixed 60 lower roll adapted for free rotation, trapped springs supporting said fixed roll against downward pressure, a handle member, journal bear-

ings extending downwardly at right angles to said handle member and adapted for lateral shifting by lateral arcuate movement of said handle member, an upper roll journaled for free rotation in said bearings, vertical driving means constantly in mesh with horizontal twin driving means adapted for opposite rotation, a gear on said wringer roll, and gears on said horizontal driving means positioned to receive the gear on said roll when the latter is shifted.

5. In a reversible wringer, a manually shiftable wringer roll, vertical driving means constantly in mesh with twin horizontal driving means adapted for opposite rotation, a gear on 10 said wringer roll, gears on said horizontal driving means positioned to mesh with the gear on said roll when the latter is shifted, and means for maintaining said roll gear in meshed position.

6. In a reversible wringer, a frame, a lower roll 15 fixed therein and adapted for free rotation, trapped springs supporting said roll against downward pressure, a handle member, journal bearings extending downwardly at right angles to said handle member and adapted for lateral 20 shifting by lateral arcuate movement of said handle member, an upper roll journaled for free rotation in said bearings, vertical driving means constantly in mesh with twin horizontal driving means adapted for opposite rotation, a gear on 25 said wringer roll, gears on said horizontal driving means positioned to receive the gear on said roll when the latter is shifted, and means for maintaining said roll gear in meshed position.

7. In a reversible wringer, a frame, a lower 30 roll fixed therein and adapted for free rotation, trapped springs supporting said roll against downward pressure, a handle member, journal bearings extending downwardly at right angles to said handle member and adapted for lateral 35 shifting by lateral arcuate movement of said handle member, an upper roll journaled for free rotation in said bearings, vertical driving means constantly in mesh with twin horizontal driving means adapted for opposite rotation, a gear on 40 said wringer roll, gears on said horizontal driving means positioned to receive the gear on said roll when the latter is shifted, detent pins on said frame, and means on said journal bearings for engaging the pins to maintain said roll 45 gear in meshed position.

8. In a reversible wringer, a frame, a lower roll 50 fixed therein and adapted for free rotation, trapped springs supporting said roll against downward pressure, a handle member, journal 55 bearings extending downwardly at right angles to said handle member and adapted for lateral shifting by lateral arcuate movement of said handle member, an upper roll journaled for free rotation in said bearings, vertical driving means constantly in mesh with twin horizontal driving means adapted for opposite rotation, a gear on 60 said wringer roll, gears on said horizontal driving means positioned to receive the gear on said roll when the latter is shifted, detent pins on said 65 frame, and means on said journal bearings to engage the pins and co-act with the trapped springs to maintain said roll gear in meshed position.

9. In a reversible wringer, a frame, a lower 70 roll fixed therein and adapted for free rotation, trapped springs supporting said roll against downward pressure, a handle member, journal

bearings at the ends of said handle extending downwardly at right angles thereto and adapted for lateral shifting by lateral arcuate movement of said handle member, an upper roll journaled for free rotation in said bearings, vertical 5 driving means constantly in mesh with twin horizontal driving means adapted for opposite rotation, a gear on said wringer roll, gears on said horizontal driving means positioned to receive the gear on said roll when the latter is shifted, 10 detent pins on said frame, and cam faces formed exteriorly of said journal bearings adapted to engage the pins to maintain said roll gear in meshed position.

10. In a reversible wringer, a frame, a lower 15 roll fixed therein and adapted for free rotation, trapped springs supporting said roll against downward pressure, a handle member, journal bearings at the ends of said handle extending downwardly at right angles thereto and adapted 20 for lateral shifting by lateral arcuate movement of said handle member, an upper roll journaled for free rotation in said bearings, vertical driving means constantly in mesh with twin horizontal 25 driving means adapted for opposite rotation, a gear on said wringer roll, gears on said horizontal driving means positioned to receive the gear on said roll when the latter is shifted, detent pins on said frame, and cam faces formed exteriorly of said journal bearings adapted to 30 engage the pins and co-act with the trapped springs for maintaining said roll gear in meshed positions.

11. In a reversible wringer, a frame, a lower 35 roll fixed therein and adapted for free rotation, trapped springs supporting said roll against downward pressure, a handle member, journal bearings at the ends of said handle extending downwardly at right angles thereto and adapted 40 for lateral shifting by lateral arcuate movement of said handle member, an upper roll journaled for free rotation in said bearings, vertical driving means constantly in mesh with twin horizontal 45 driving means adapted for opposite rotation, a gear on said wringer roll, gears on said horizontal driving means positioned to receive the gear on said roll when the latter is shifted, detent pins on said frame, and cam faces formed exteriorly of said journal bearings adapted to 50 engage the pins and co-act with the trapped springs for maintaining said roll gear in meshed position, the detent pins being spaced to permit the removal of handle member and bearings when the latter are vertically disposed.

12. In a reversible wringer, a frame, a lower 55 roll fixed therein and adapted for free rotation, trapped springs supporting said roll against downward pressure, a handle member, journal bearings extending downwardly at right angles to said handle member and adapted for lateral 60 shifting by lateral arcuate movement of said handle member, an upper roll journaled for free rotation in said bearings, vertical driving means constantly in mesh with twin horizontal driving means adapted for opposite rotation, a gear on 65 said wringer roll, gears on said horizontal driving means positioned to receive the gear on said roll when the latter is shifted, detent pins extending inwardly horizontally on said frame, and means on said journal bearings for engaging the pins to maintain said roll gear in meshed position.

JOHN B. CASTINO.
